Albert F. Hendershott

UNITED STATES PATENT OFFICE.

ALBERT F. HENDERSHOTT, OF WASHINGTON, DISTRICT OF COLUMBIA.

ROLL-PAPER HOLDER AND CUTTER.

SPECIFICATION forming part of Letters Patent No. 415,199, dated November 19, 1889.

Application filed February 7, 1889. Serial No. 299,085. (No model.)

To all whom it may concern:

Be it known that I, ALBERT F. HENDERSHOTT, a citizen of the United States, residing at Washington, in the District of Columbia, have invented certain new and useful Improvements in Roll-Paper Holders and Cutters; and I do hereby declare the following to be a full, clear, and exact description of the invention, such as will enable others skilled in the art to which it appertains to make and use the same.

My invention relates to means for supporting and paying off roll, wrapping, or other paper, and its object is to provide means by which such paper may be used and handled in a convenient way, and by which any length or strip required may be torn or cut from the roll.

It consists, first, in the combination of a frame, with a base, two uprights, and a cross bar or roller, upon which is mounted a roll of paper.

It consists, secondly, in the combination of a roll-of-paper hanger or frame with a coil-spring in each of the uprights of the frame, and which press upon the shaft, which passes through the india-rubber-coated roller, which presses firmly upon the base or paper passing between the base and the roller, controlling the forward and backward motion of the paper.

It consists, thirdly, in the combination of a roll-of-paper hanger or frame, a rubber-coated roller, and a knife, the knife being so adjusted as to pass in front of the roller and permit the paper to be easily taken hold of and torn in the usual well-known way.

It consists, fourthly, in the combination of a coil-spring in the uprights of the frame, which presses upon the shaft passing through the rubber-coated roller. Upon the end of this shaft there is a crank-wheel by which the roller is operated. One or more turns of the wheel will throw the paper forward of the knife, so it may be easily grasped by the thumb and finger and drawn against the knife and be cut or torn in the usual well-known way.

In the drawings, Figure 1 is a front elevation of my device with parts broken away. Fig. 2 is a vertical cross-section on the line x of Fig. 1.

A represents the base upon which the uprights are fastened, and upon which the rub-

ber-coated roller is continually pressed by 55 the coiled springs.

B represents the uprights of the frame upon which C, the cross bar or roller holding the roll of paper, is fastened by a rod passing through the roller and uprights and fastened 60 in place with a screw.

D is the roll of paper mounted upon the cross bar or roller.

E is the rubber-coated roller by which the paper is thrown forward of the knife. 65

F shows the crank-wheel on the end of the shaft of the rubber-coated roller, by which it is operated.

G shows the knife fastened to the base, under which the paper is thrown by operating 70 the crank-wheel on the end of the rubber roller.

By my invention the paper is easily and conveniently handled, and any size or length of sheet may be cut or torn off by laying 75 hold of the loose end and pulling it across the knife-edge in the well-known way.

The complete device may be placed in any position required and work equally well. It may be fastened under the counter, on the side 80 of the wall, or fastened to the shelving or standing across the counter, stand, or table.

I am aware that prior to my invention roll-paper and cutting devices have been made. I therefore do not claim such a combination, 85 broadly; but

What I do claim as my invention, and desire to secure by Letters Patent, is—

The combination, with the base, the uprights, and the roller C, journaled in said uprights, of the shaft parallel with the said roller, the springs arranged within the lower ends of the uprights and pressing on the extended ends of said shaft, said extended ends working in vertical slots in the uprights, and one of said ends provided with a crank-wheel, the rubber roller on said shaft, and the fixed inclined knife arranged in advance of the rubber roller, extending entirely across the space between the uprights, with 90 its acting edge on the same longitudinal plane as the bottom edge of the rubber roller, substantially as shown and described. 95 100

ALBERT F. HENDERSHOTT.
